US00D786471S

(12) **United States Design Patent** (10) Patent No.: **US D786,471 S**
 Snell et al. (45) Date of Patent: ** *May 9, 2017

(54) TROFFER-STYLE LIGHT FIXTURE	6,578,979 B2	6/2003	Truttmann-Battig	362/92
6,598,998 B2	7/2003	West	257/E33.073	
(71) Applicant: CREE, INC. , Durham, NC (US)	D496,121 S *	9/2004	Santoro	D26/74
6,871,983 B2	3/2005	Jacob et al.	362/364	
(72) Inventors: Nathan Snell , Raleigh, NC (US); Brian Kinnune , Racine, WI (US)	6,948,838 B2	9/2005	Kunstler	362/237
6,948,840 B2	9/2005	Grenda et al.	362/555	
6,951,415 B2	10/2005	Amano	362/297	
7,021,797 B2	4/2006	Minano et al.	362/355	
(73) Assignee: CREE, INC. , Durham, NC (US)	7,049,761 B2	5/2006	Timmermans et al.	315/246
(*) Notice: This patent is subject to a terminal disclaimer.	7,063,449 B2	6/2006	Ward	345/102
(**) Term: 14 Years	7,111,969 B2	9/2006	Bottesch	362/299
(21) Appl. No.: 29/466,391	7,175,296 B2	2/2007	Cok	362/147
(22) Filed: Sep. 6, 2013	7,213,940 B1	5/2007	Van de Ven et al.	362/231
(51) LOC (10) Cl. 26-05	7,217,004 B2	5/2007	Park	362/240
(52) U.S. Cl. USPC D26/74	7,237,924 B2	7/2007	Martineau et al.	362/231
(58) Field of Classification Search	D556,358 S	11/2007	Santoro	D26/74

(57) CLAIM

The ornamental design for a troffer-style light fixture, as shown and described herein.

DESCRIPTION

FIG. 1 is a perspective view of a light fixture according to an embodiment of the present invention.

FIG. 2 is a left side elevation view of a light fixture according to an embodiment of the present invention, with the right side being a mirror image.

FIG. 3 is a front end elevation view of a light fixture according to an embodiment of the present invention, with the back end elevation view being identical.

FIG. 4 is a bottom plan view of a light fixture according to an embodiment of the present invention.

FIG. 5 is a top plan view of a light fixture according to an embodiment of the present invention.

FIG. 6 is a close-up left side elevation view of a portion of a light fixture according to an embodiment of the present invention.

FIG. 7 is a cross-sectional view along cut line 7-7 of a light fixture according to an embodiment of the present invention.

FIG. 8 is a perspective view of a light fixture according to an embodiment of the present invention.

FIG. 9 is a left side elevation view of a light fixture according to an embodiment of the present invention, with the right side being a mirror image.

FIG. 10 is a front end elevation view of a light fixture according to an embodiment of the present invention, with the back end elevation view being identical.

FIG. 11 is a bottom plan view of a light fixture according to an embodiment of the present invention.

FIG. 12 is a top plan view of a light fixture according to an embodiment of the present invention.

FIG. 13 is a close-up left side elevation view of a portion of a light fixture according to an embodiment of the present invention.

FIG. 14 is a cross-sectional view along cut line 14-14 of a light fixture according to an embodiment of the present invention.

FIG. 15 is a perspective view of a light fixture according to an embodiment of the present invention.

FIG. 16 is a left side elevation view of a light fixture according to an embodiment of the present invention, with the right side being a mirror image.

FIG. 17 is a front end elevation view of a light fixture according to an embodiment of the present invention, with the back end elevation view being identical.

FIG. 18 is a bottom plan view of a light fixture according to an embodiment of the present invention.

FIG. 19 is a top plan view of a light fixture according to an embodiment of the present invention.

FIG. 20 is a close-up left side elevation view of a portion of a light fixture according to an embodiment of the present invention.

FIG. 21 is a cross-sectional view along cut line 18B-18B of a light fixture according to an embodiment of the present invention.

FIG. 22 is a perspective view of a light fixture according to an embodiment of the present invention.

FIG. 23 is a left side elevation view of a light fixture according to an embodiment of the present invention, with the right side being a mirror image.

FIG. 24 is a front end elevation view of a light fixture according to an embodiment of the present invention, with the back end elevation view being identical.

FIG. 25 is a bottom plan view of a light fixture according to an embodiment of the present invention.

FIG. 26 is a top plan view of a light fixture according to an embodiment of the present invention.

FIG. 27 is a close-up left side elevation view of a portion of a light fixture according to an embodiment of the present invention.

FIG. 28 is a cross-sectional view along cut line 28-28 of a light fixture according to an embodiment of the present invention.

FIG. 29 is a perspective view of a light fixture according to an embodiment of the present invention.

FIG. 30 is a left side elevation view of a light fixture according to an embodiment of the present invention, with the right side being a mirror image.

FIG. 31 is a front end elevation view of a light fixture according to an embodiment of the present invention, with the back end elevation view being identical.

FIG. 32 is a bottom plan view of a light fixture according to an embodiment of the present invention.

FIG. 33 is a top plan view of a light fixture according to an embodiment of the present invention.

FIG. 34 is a close-up left side elevation view of a portion of a light fixture according to an embodiment of the present invention.

FIG. 35 is a cross-sectional view along cut line 30B-30B of a light fixture according to an embodiment of the present invention.

FIG. 36 is a perspective view of a light fixture according to an embodiment of the present invention.

FIG. 37 is a left side elevation view of a light fixture according to an embodiment of the present invention, with the right side being a mirror image.

FIG. 38 is a front end elevation view of a light fixture according to an embodiment of the present invention, with the back end elevation view being identical.

FIG. 39 is a bottom plan view of a light fixture according to an embodiment of the present invention.

FIG. 40 is a top plan view of a light fixture according to an embodiment of the present invention.

FIG. 41 is a close-up left side elevation view of a portion of a light fixture according to an embodiment of the present invention.

FIG. 42 is a cross-sectional view along cut line 42 of a light fixture according to an embodiment of the present invention.

FIG. 43 is a perspective view of a light fixture according to an embodiment of the present invention.

FIG. 44 is a left side elevation view of a light fixture according to an embodiment of the present invention, with the right side being a mirror image.

FIG. 45 is a front end elevation view of a light fixture according to an embodiment of the present invention, with the back end elevation view being identical.

FIG. 46 is a bottom plan view of a light fixture according to an embodiment of the present invention.

FIG. 47 is a top plan view of a light fixture according to an embodiment of the present invention.

FIG. 48 is a close-up left side elevation view of a portion of a light fixture according to an embodiment of the present invention.

FIG. 49 is a cross-sectional view along cut line 49-49 of a light fixture according to an embodiment of the present invention.

FIG. 50 is a perspective view of a light fixture according to an embodiment of the present invention.

FIG. 51 is a left side elevation view of a light fixture according to an embodiment of the present invention, with the right side being a mirror image.

FIG. 52 is a front end elevation view of a light fixture according to an embodiment of the present invention, with the back end elevation view being identical.

FIG. 53 is a bottom plan view of a light fixture according to an embodiment of the present invention.

FIG. 54 is a top plan view of a light fixture according to an embodiment of the present invention.

FIG. 55 is a close-up left side elevation view of a portion of a light fixture according to an embodiment of the present invention.

FIG. 56 is a cross-sectional view along cut line 48B-48B of a light fixture according to an embodiment of the present invention.

FIG. 57 is a perspective view of a light fixture according to an embodiment of the present invention.

FIG. 58 is a left side elevation view of a light fixture according to an embodiment of the present invention, with the right side being a mirror image.

FIG. 59 is a front end elevation view of a light fixture according to an embodiment of the present invention, with the back end elevation view being identical.

FIG. 60 is a bottom plan view of a light fixture according to an embodiment of the present invention.

FIG. 61 is a top plan view of a light fixture according to an embodiment of the present invention.

FIG. 62 is a close-up left side elevation view of a portion of a light fixture according to an embodiment of the present invention; and,

FIG. 63 is a cross-sectional view along cut line 63-63 of a light fixture according to an embodiment of the present invention.

Some elements of the fixtures in some of the figures are in broken lines for illustrative purposes only and form no part of the claimed design.

The break lines in some of the figures indicate that the portions shown within the break lines form no part of the claimed design.
